[57] ABSTRACT

A moistening arrangement for moistening a flap of an envelope has a nozzle directed to spray a liquid at the envelope flap along a given locus in the plane in response to signals that are a function of the width of the flap for moistening the flap at determined positions thereof. A sensor is positioned to detect the presence of liquid emitted from the nozzle. A control arrangement controls application of liquid to the nozzle while an envelope is adjacent thereto, and liquid is momentarily directed to the nozzle prior to movement of an envelope adjacent to the nozzle for providing an indication of operability of the nozzle and liquid applying arrangement.

VERIFICATION OF OPERABILITY OF MOISTENER

BACKGROUND OF THE INVENTION

This invention relates to a method and apparatus for determining the operability of a moistening arrangement for applying moisture to the gummed flaps of envelopes or the like, especially for ensuring the proper moistening of gummed flaps in a high speed mailing machine.

U.S. Pat. No. 3,911,862 discloses a moistening system for envelope flaps wherein a pair of fixed nozzles are aligned to selectively spray water against an envelope flap, in dependence upon the output of a sensor arranged to detect the location of the edge of the flap in the plane perpendicular to the direction of motion of the envelope that passes through the nozzles. Thus, a first of the nozzles is controlled to spray water at the flap if the sensor does not detect the envelope flap, and the other of the nozzles sprays water if the sensor does detect the envelope. In this arrangement, another sensor is arranged to control the supply of water to the nozzles when the leading edge of the envelope passes a determined position, and to inhibit the supply of water to the nozzles when the trailing edge of the envelope has passed that position. In an alternative arrangement, instead of employing two (or more) nozzles, the reference discloses the movement of a single nozzle between two end positions by means of a solenoid, under the control of the output of the flap edge position sensor, or under the control of feedback from a contoured template.

The system disclosed in the above reference, however, is not adapted to the high speed moistening of envelopes, especially since consideration is not given to the rapid change of the position of the moistener nozzle required for high speed movement of the envelopes. In addition, the above system turns the spray from the nozzle on and off solely in response to the sensing of the leading and trailing edges of the envelope, independently of the configuration of the flap, and is not adapted to compensation for response times of various movable elements of the system or control of the moisture necessary for properly moistening the envelope flaps.

SUMMARY OF THE INVENTION

Briefly stated, the present invention provides a moistening arrangement for moistening a flap of an envelope, wherein the flap moves in a first direction in a given plane. The arrangement has a nozzle directed to spray a liquid at the envelope flap along a given locus in the plane. A source of first signals is provided that are a function of the width of the flap. Means are provided that are responsive to the first signals for moving the nozzle in a direction substantially parallel to the plane for moistening the flap at determined positions thereof. Means are also provided for applying the liquid to the nozzle. Means are provided for controlling the liquid applying means, and a sensor is positioned to detect the presence of liquid emitted from the nozzle. The control means comprises means for controlling the liquid applying means to direct liquid to the nozzle while an envelope is adjacent thereto, and means are provided for momentarily directing liquid to the nozzle prior to movement of an envelope adjacent to the nozzle for

providing an indication of operability of the nozzle and liquid applying means.

In accordance with a further feature of the invention, a moistening system comprises means for moving an article to be moistened to a moistening station. The moistening station comprises means for supplying a moistening liquid to a nozzle for moistening an article moved to the station. A sensor is positioned to detect a spray of moisture from the nozzle, and control means momentarily controls the application of the liquid to the nozzle in the absence of an article at the station.

The control means may comprise means for moving the nozzle from a first position displaced from the path of movement of the article, to at least one position adjacent the path, with the sensor being positioned adjacent the first position. The article to be moistened is preferably an envelope having a flap with a gummed portion thereon, and the means for moving preferably comprises means for moving the nozzle from the first position to at least one position adjacent the gummed portion of the flap.

In accordance with a further feature of the invention, a method is provided for moistening a gummed flap of an envelope comprising momentarily applying a liquid to a nozzle, sensing the spray of the liquid from the nozzle, then moving the nozzle to at least one position adjacent the gummed flap and then applying liquid to the flap for moistening the flap.

BRIEF FIGURE DESCRIPTION

In order that the invention may be more clearly understood, it will now be disclosed in greater detail with reference to the accompanying drawings, wherein:

FIG. 1 is a simplified side view of a mailing machine which may incorporate the moistener of the invention;

FIG. 2 is a top view of the mailing machine of FIG. 1;

FIG. 3 is a simplified diagram of a moistening system in accordance with the invention;

FIG. 4 is a simplified diagram illustrating the nozzle control arrangement of the invention;

FIG. 5 is a partial end view of the moistener with the nozzle in its most forward position;

FIG. 6 is a partial end view of the moistener with the nozzle in its most rearward position;

FIG. 7 is an enlarged view of the nozzle control arrangement;

FIG. 8 is an illustration of the sensing arrangement for determining the operating condition of the moistener;

FIG. 9 is an illustration of a modification of the sensing arrangement;

FIG. 10 is a schematic diagram of a circuit that may be employed for the sensor;

FIG. 11 is a simplified end view of the moistener illustrating the relative positions of the moistener and the flap sensor;

FIGS. 12-14 illustrate sequential positions of the nozzle during the moistening of a flap;

FIG. 15 is a partial cross-sectional view of a pump assembly for the liquid, in accordance with one embodiment of the invention;

FIG. 16 is a plan view of a portion of the pump assembly of FIG. 15; and

FIG. 17 is a chart showing how the moistener commands are calculated.

DETAILED DISCLOSURE OF THE INVENTION

A mailing machine of the type with which the present invention may be employed is illustrated generally in FIGS. 1 and 2. As illustrated, mail may be stacked on a mailing machine in the region 100 disclosed. The mail is fed from the stacking region 100 to a singulator 101 for separation of individual pieces of mail. Following the separation of individual envelopes, the envelopes pass a flap profile sensors 103 to provide electrical signals for storage in a memory 104,222, described subsequently corresponding to the profile of the envelope flap. Data stored in the memory 104 is employed to control the movement of a moistener 105, to which the present invention is directed. The moistener is moved to spray water on the adhesive region of the envelope flap, as will be discussed. Following moistening, the envelope flaps are sealed in a sealing region 106, and directed to a weigher 107. Following weighing by the weigher 107, indicia may be printed on the envelopes by a suitable printer and inker assembly 108.

It is of course apparent that the moistening arrangement of the present invention may alternatively be employed in any suitable systems.

A preferred embodiment of a moistening system in accordance with the invention is illustrated in further detail, along with the adjacent elements of a mailing machine, in FIG. 3. As illustrated in FIG. 3, mail is directed in the direction of arrow 200 unto a drive deck 201, which may be horizontal or slightly inclined. The mail is separated into individual pieces at singulator drive 202, the drive being depicted by drive roll 203 driven by a motor 204. The motor is controlled by a microcomputer 205. While reference is made in this application to drive rollers, it is apparent that drive belts may also be employed for the function of transporting the mail along the deck 201. Prior to being directed to the singulator, the flaps of the mail had been opened by any suitable technique, to extend downwardly through a slot in the deck 201. A rear guide wall (not shown) 40 may be provided for latterly guiding the mail. It is thus apparent that individual envelopes are driven by singulator drive 202, in the direction of arrow 201.

In accordance with one feature of the invention, it is necessary to provide a signal corresponding to the speed of envelopes having flaps to be moistened by the moistener 105. It has been found that the rotational or other movements in the singulator drive are not sufficiently accurate for the purpose of controlling the position of a moistener, in view of the slip which normally occurs in the singulator. Accordingly, an encoding roll 210 is provided down stream of the singulator, the rotation of the roll 210 being encoded by an encoder 211, to provide a pulse train of pulses to the microcomputer 205 corresponding to the instantaneous rate of rotation of the roll 210. Envelopes (not shown in FIG. 3) are directed to press against the roll 210 by a bias roller 212. The roll 210 may be provided with suitable markings 216 about its periphery adapted to be sensed by photo sensor 217, for applying speed related impulses to the encoder 211. It is of course apparent that other techniques may be employed for applying signals corresponding to the speed of rotation of the encoder roll 210 to the microcomputer 205.

The envelopes merging from the nip of the encoder roll 210 and bias roll 212 are directed, as indicated by the arrow 220, to the flap profile sensors. These sensors direct signals corresponding to the instantaneously sensed

velocity of an envelope flap passing thereby, to the microcomputer 205, for storage in a memory 222. The sensor 220 is preferably adapted to sense the flap width at predetermined longitudinally spaced apart intervals, for example, at times corresponding to predetermined numbers of pulses output from the encoder 211.

Downstream from the flap profile sensors, the nozzle 250 of the moistening system 105 is moved by the nozzle drive 251 under the control of the microcomputer 205, to position the nozzle at a location corresponding to the width of the flap of the envelope then positioned at the moistening station. The intended position of the nozzle is hence controlled as a function of the data stored in the memory 222 in response to the output of the flap profile sensors, the velocity stored in the memory 222 in response to the output of the encoder 211, and the known distance between the flap profile sensor and the moistening station.

The microcomputer 205 also controls a pump 260 for directing a determined quantity of liquid from the liquid supply 261 to the nozzle 250 by way of tube 261. Thus, the microcomputer receives data corresponding to the length of the area to be moistened on an envelope, from the flap sensor. Further data may be stored in memory corresponding to standard envelope flaps, so that the microcomputer can determine the shape of the flap to be moistened on the basis of a minimum number of initial sensings of flap width. This information may be employed by the microcomputer to control the quantity of liquid to be pumped by the pump 260.

In accordance with the invention, a sensor 280 may be provided at a determined position of the nozzle, for example at an initial position of the nozzle out of alignment with the flap to be moistened. Prior to controlling the nozzle drive in preparation to moistening the flap of an envelope, the microcomputer controls the pump 260 to emit a jet of liquid from the nozzle for a predetermined time. The sensor 280 is positioned to intercept this jet, either by transmission or reflection, to provide a signal to the microcomputer that the jet nozzle is functioning properly, and that the liquid supply 261 is adequately filled to moistened the flap of the envelope currently being directed to the moistener. Downstream of the moistener, the envelope is directed to the nip between a drive roller 300 and its respective back up roller 301. The drive roll 300 is controlled by motor drive 302 under the control of the microprocessor 205. The drive roller 300 is spaced from the drive roller 203 a distance such that the envelope is continually positively driven. It will be observed, however, that due to the spacing between the encoder roller 210 and the drive wheel 300, the encoder 211 will not provide timing pulses corresponding to the speed of movement of the envelope as the trailing edge of the flap passes the nozzle 250. At this time, the speed of the envelope, for the purposes of positioning the nozzle 250, is determined by the microcomputer, and corresponds to the speed of which the microcomputer controls the roll 300. Since the roll 300 does not form part of a singulator, it is not necessary to consider slippage between the speed of the envelope and the rotational speed of the roller, and hence it is not necessary to provide an additional encoder wheel downstream of the moistener.

Following the drive roller 300, the envelope may be directed to a weigher 107 for further processing. Prior to passing to the weigher, the flap may be folded by suitable means to contact the remainder of the envelope, for sealing.

A preferred mechanism for controlling the nozzle is illustrated in FIGS. 4, 5 and 6. As illustrated in these figures, the nozzle 250 is connected by way of the flexible tube 261 to the pump 260. The nozzle is held on a slide 400 slidably mounted on a pair of fixed guide rods 401, 402. As illustrated in FIGS. 5 and 6, the guide rods extend below the deck 201 at angle, for example, 25° to the horizontal. An operating link 403 is pivoted to the slide 400, and guided in a guide block 404 affixed to the guide rods for movement parallel to the guide rods.

A servo motor 410, mounted on a fixed frame 411, as illustrated in FIGS. 5 and 6, is connected to the microcomputer 205 for controlling the position of the nozzle. The motor 410 has a pinion 412 on its shaft, coupled to a gear 413 on shaft 414 mounted for rotation in the frame 411. Gear 415 on the shaft 414 drives a gear 416 also mounted in the frame 411. A link 417 affixed for rotation with the gear 416, is pivoted to the lower end of the link 403. As a consequence, the rotational displacement of the shaft of the servo motor 410 is coupled to move the slide 400 along the guide rods 401, 402, between a uppermost position illustrated in FIGS. 4 and 5, and a lower position as illustrated in FIG. 6. The lowermost position is also illustrated in FIG. 4.

As illustrated in FIG. 5, an envelope 450 positioned for movement along the deck 201 has a flap 451 extending through the gap between an edge 452 of the deck and the lateral guide wall 453. The flap is guided to extend in a plane parallel to the plane of guide rods 401, 402 by an inclined guide wall 454. The nozzle 250 is directed to spray water downward against the gummed side of the flap, as illustrated in FIG. 5. As more clearly illustrated in FIG. 7, the guide block 404 has a slot 460 for receiving the link 403, in order to permit the necessary lateral movement of the lower end of the link 403 upon rotation of the link 417.

The sensor 280 for sensing the spray of water from the nozzle may be mounted in the guidewall 454, as illustrated in FIGS. 4 and 5. The sensor may be positioned to directly receive the spray from the nozzle, as illustrated in FIG. 8, wherein the sensor 280 is a reflective sensor and includes a radiation emitter 490 and a radiation detector 491. The sensor 280 is positioned laterally of the path of the spray, so that, in the presence of the water spray, radiation from the emitter is reflected back to the detector, to indicate the presence of a correct spray.

A preferred circuit for coupling the sensor 280 to the microcomputer is illustrated in FIG. 10, wherein a light emitting diode 500 is continually connected to the operating voltage source by way of a resistor 501, and the current path of phototransistor 502 is also continually connected to the operating source by way of a resistor 503. The collector of the phototransistor is coupled to the microcomputer by way of a capacitor 504. It is thus apparent that changes in the radiation from the photodiode 500 reaching the phototransistor, such as occurs during the momentary spraying of water at the photo-sensor, results in a pulse coupled to the microprocessor by way of the capacitor.

Referring again to FIG. 4, it is apparent that the individual detectors and emitters 495 of the profile sensor 103 extend in a row parallel to the direction of movement of the nozzle 250, and are spaced therefrom a distance d. As further illustrated in FIG. 11, the row of sensors 103 are also inclined to the horizontal substantially the same angle as the guide rods 401, 402.

As illustrated in FIGS. 12-14, in accordance with the invention the nozzle 250 may be continually moved in alignment with the gummed region 510 of a flap, as the envelope is moved along the deck in the direction of the arrow 511.

A preferred embodiment of a pump 260 for pumping the liquid, for example water, to the nozzle, is illustrated in FIGS. 15 and 16. This pump is illustrated as having two cylinders 600, 601 coaxially mounted at spaced 10 apart positions on a frame 603, i.e. the frame of the mailing machine. A servo motor 603 has a shaft 604 adapted to rotate disk 605. The disk 605 carries a projection 606 that extends into a slot 607 in an arm 608 extending perpendicularly from a piston shaft 609. The 15 piston 609 carries pistons 610, 611 on opposite ends thereof which extend into the cylinders 600, 601 respectively. The liquid supply 261 is coupled to each of the cylinders by way of tubing 620 and inlet valves 621, 622 respectively. Outlet valves 623, 624 of the cylinders are 20 coupled to the tubing 261 for supplying liquid to the nozzle 250. As illustrated in FIG. 16, a sensor 630 may be provided, cooperating with a marking 631 or the like of the disk 605, to enable signalling to the microprocessor of the center positioning of the two pistons.

25 It will of course be apparent that, if desired, only a single cylinder and piston arrangement may be provided, if desired.

In the illustrated pump, the motor 603, adapted to be connected to the microcomputer, is controlled by the 30 microcomputer to rotate each shaft a determined amount, depending upon the desired amount of liquid to be supplied to the nozzle. The rotation of the shaft of the motor, and the resultant angular displacement of the pin 606, results in linear movement of the piston shaft 609, and hence of the pistons affixed thereto. The piston forces the liquid from this cylinder by way of their respective output valve 623, 624, and to the nozzle 250 by way of the tubing 267. Reverse rotation of the shaft 604 effects the drawing of liquid from the supply 261 35 into the respective cylinder 600, 601. The sensor 630, responsive to the position of the marking 631, enables the microcomputer to reposition the shaft 604 in a central position, so that the amount of liquid dispensed can be accurately controlled. The arrangement illustrated in 40 FIGS. 15 and 16 thereby enables full control of the amount of liquid applied to the nozzle for the moistening of each flap. The aperture of the nozzle 250 is preferably sufficiently small that the nozzle act as a hypodermic needle, i.e. so that the amount of flow is independent of the pressure applied thereto from the pump. This results in an even distribution of liquids sprayed 45 throughout the gummed portion of the envelope flap.

As discussed above, the flap profile sensor 103 generates a signal periodically (for example for every inch of movement of the envelope), and this information is stored in a table in the memory 222. The envelope velocity is also periodically sensed and stored in the memory 222. This data along with the response time of the moistening assembly, is needed in order to correctly position the nozzle. It is further necessary to enter the distance of travel of the envelope, from the profile sensor to the nozzle, for determining the correct position of the nozzle.

65 In accordance with one embodiment of the invention, the slope of the flap, i.e. the rate of change of width of the flap between successive sensing periods, is determined. This function is of course a function of the velocity of movement of the envelope. If the slope deter-

mined by the microcomputer is below a predetermined level, it is possible to control the movement of the nozzle in the servo mode, i.e. the motor is controlled directly by conventional means in response to the detected slope. If the slope is greater than a predetermined level, however, such that the motor cannot respond adequately quickly to correctly position the nozzle, then conventional circuitry is employed to operate the motor in a torque mode, i.e. by directing a current pulse of determined magnitude and duration to the motor to properly drive the nozzle.

The flap position table responsive to the output of the flap sensor is built in the microcomputer by reading the flap width for every "k" in encoder counts, i.e. fixed distances. If the response time of the nozzle control motor is considered to be substantially zero, then it is merely necessary to fetch a value from the table which corresponds to the distance d (from the flap detector to the nozzle, from the currently read flap reading). In other words, in this case the microcomputer points to a position in the table that is d/k positions displaced from the currently read position, in order to determine the flap width at the position of the nozzle. Since the response time of the nozzle adjustment system is not zero, it is of course necessary to subtract this response time from the distance d .

The distance x that the envelope travels during the response time of the moving parts of the moistener may be shown to be equal to:

$$x = Tr * V + C$$

where Tr is the response time of the moistener, V is the detected velocity of the envelope, and $C = a * Tr^2 / 2$, and a is the calculated acceleration of the envelope. The number n of positions in the table (i.e. from the position that corresponds at that instant to the position of the nozzle), is hence:

$$n = (d - x) / k$$

In accordance with the invention, as illustrated in FIG. 17, a quantity b that is a function h of the detected rate of change a of the flap width is stored in a first table in the memory. A second table is prepared, storing a function c of the function h and the response distance b , at times responsive to determined numbers of pulse outputs of the envelope velocity encoder. A third table is also prepared for storing a function y of the velocity v of the envelope. The actual command z to the moistener, then, is a function f of the stored functions c and y .

When the slope of the flap profile exceeds a certain value, the servo mode of motor control is not sufficient in tracking, and torque mode must be used.

The slope of the edge of the envelope is calculated by looking at the value of the flap position at the beginning and the end of a predefined section of the envelope. The 1st section is from the point where the flap changes from zero to a point at, for example, one inch from the zero point. If the value of the flap position at this point exceeds a certain value, then torque control of the motor should be used. The value of the torque and the duration for which it should be applied, is a function of the slope (flap position in this case). The slope of the next section will determine the type of the envelope. If it one type, the tracking will continue in servo mode until a further point. Otherwise, the process will look for the envelope tip. This is done by comparing a pair of adjacent points. When the second compared point is less

than the previous point, it means that the envelope tip has been detected, where again some torque is needed to overcome the change in direction of the flap profile. This torque is also a function of the slope. At the point where the flap detector sense the flap's end, the actual position of the nozzle is fetched (the next command to be used), and if the nozzle is more than a predefined distance from home, torque mode is applied to return it home faster.

Generally it is desirably that the slope be calculated more often, so that every change will be detected and the appropriate nozzle command will be generated. There are two processes that will take place concurrently, the process of generating the nozzle command for the servo mode, and the process of generating command for torque mode which should override the servo mode if TFF (turbo mode) is to be employed. The torque mode is time based in a sense that it is to be in effect starting t_1 milliseconds from the present and then lasting for t_2 ms. algorithm:

Every one inch the slope of the flap is calculated. There are 8 positive levels and 8 negative levels of slope.

The new slope and the old slope serves as pointers to a table: the entries of this table includes, Torque/Servo. Torque value, Duration. The last signals if torque mode is to be applied; the others are the value, and the time for this interval.

If torque mode is needed, the delay time before it is applied is calculated.

The general for this calculation is:

$$x = V_0 + a * t^2 / 2$$

where V_0 is the velocity at the present, a is the slope of the velocity profile, x_0 is the distance, and t is the time to reach distance ' x '. If $x = d$, $a = V_p / T_p$ and solving for ' t ' as a function of V_0 :

$$t * t + 2V_0 * t / a - 2d / a = 0$$

$$t = -1.06V_0 + \text{sqr} (1.12V_0 * V_0 + 7870)$$

From this result, a table can be constructed, and the delay time to be fetched according to the measured velocity.

Some adjustments may be made, if desired, to reflect the flat part of the velocity profile, and the distance passed during response time.

While the invention has been disclosed with reference to a limited number of embodiments, it will be apparent that variation and modifications may be made therein, and it is therefore intended in the following claims to cover each such variation and modification as falls within the true spirit and scope of the invention.

What is claimed is:

1. In a moistening apparatus for moistening a flap of an envelope, the flap moving in a first direction in a given plane, said apparatus having a nozzle directed to spray a liquid at the envelope flap along a given locus in said plane, means for moving the nozzle between first and second positions, a source of first signals that are a function of the width of said flap, means responsive to said first signals for moving said nozzle in a direction substantially parallel to said plane for moistening said flap at determined positions thereof, and means for applying said liquid to said nozzle; the improvement

comprising means for controlling said liquid applying means, and a sensor fixedly positioned at the first position to detect the presence of liquid emitted from said nozzle, when said nozzle is in said first position, said control means comprising means for controlling said liquid applying means to direct liquid to said nozzle at the second position while an envelope is adjacent thereto, and means for momentarily directing liquid to said nozzle prior to movement of said nozzle to the second position for providing an indication of operability of said nozzle and liquid applying means.

2. In a moistening apparatus wherein means are provided for moving an article to be moistened to a moistening station, and the moistening station comprises a nozzle, moving means for causing said nozzle to controllably displace between first and second positions, and means for supplying a moistening liquid to said nozzle at said second position for moistening an article moved to said station, the improvement comprising a

sensor fixedly positioned at the first position to detect a spray of moisture from said nozzle, when said nozzle is in said first position, and control means for momentarily causing the application of said liquid to said nozzle at the first position in the absence of an article at said station.

3. The moistening apparatus of claim 2 wherein said means for moving said nozzle moves the nozzle from the first position displayed from the path of movement of said article, to at least one position adjacent said path, and said sensor is positioned adjacent said first position.

4. The moistening apparatus of claim 3 wherein said article comprises an envelope having a flap with a gummed portion thereon, and said means for moving said nozzle comprises means for moving said nozzle from said first position to at least one position adjacent said gummed portion of said flap.
